CLAIM

The ornamental design for a game save transfer device for an electronic game system, as shown.

DESCRIPTION

FIG. 1 is a left side perspective view of the game save transfer device for an electronic game system of the present invention;

FIG. 2 is a left side elevational view of the game save transfer device for an electronic game system of FIG. 1;
FIG. 3 is a right side elevational view of the game save transfer device for an electronic game system of FIG. 1;
FIG. 4 is a bottom view of the game save transfer device for an electronic game system of FIG. 1;

FIG. 5 is a top view of the game save transfer device for an electronic game system of FIG. 1;

FIG. 6 is a front elevational view of the game save transfer device for an electronic game system of FIG. 1; and,

FIG. 7 is a rear elevational view of the game save transfer device for an electronic game system of FIG. 1.
